UNITED STATES PATENT OFFICE.

ARTHUR ACHESON, OF CHICAGO, ILLINOIS, ASSIGNOR TO THE LAUNDRY BLUE COMPANY, OF CHICAGO, ILLINOIS, A CORPORATION OF ILLINOIS.

PACKING AND DISPLAY BOX.

SPECIFICATION forming part of Letters Patent No. 776,042, dated November 29, 1904.

Application filed February 6, 1904. Serial No. 192,309. (No model.)

To all whom it may concern:

Be it known that I, ARTHUR ACHESON, a citizen of the United States, residing at Chicago, in the county of Cook and State of Illinois, 5 have invented certain new and useful Improvements in Packing and Display Boxes, of which the following is a specification.

This invention relates to packing-boxes which are especially adapted for shipping and 10 displaying bluing devices in the form of sticks, such as are described in Patent No. 750,847, dated February 2, 1904, although it will be understood that I do not confine the invention to this particular use and refer to it here 15 simply for convenience in setting forth the uses and advantages presented by the invention.

The object of the invention is to provide a packing-box of simple construction and ordinary shape adapted to be readily separated 20 into two display-sections for displaying the articles held therein.

I have illustrated one form in which the invention may be embodied in the accompanying 25 drawings, in which—

Figure 1 is a perspective view of the box closed. Fig. 2 is a perspective view illustrating the two sections arranged in display position.

Referring to the drawings, A and B designate the two sections of the box, which are made alike and adapted to fit together, as shown in Fig. 1, to form a rectangular box of the usual character commonly employed in commerce. The end 5 and back 6 of the box 30 form the bottom and back of section A, and the end 7 and front 8 of the box form the bottom and back of section B. Each section is provided with a short front 9, which 35 is inclosed and covered by the overlapping upper end 10 of the back when the box is closed. Each side of the box is cut diagonally from edge to edge into two parts 11 and 12, and this division is made so that the edges of 40 the sides of each section will extend from the upper edge of the front to the lower margin of the extended upper end 10 of the back, so that when the sections are fitted together to

close the box the edges of the sides of the sections will lie flush together and the overlapping extended ends 10 will lie flush against the fronts 9 and form a tight box. The sections are fastened together by nails or screws 45 50 55 60 65 70 75 80 85 90 95 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880

While I have designed the box primarily for use in holding bluing-sticks, I would have it clearly understood that the invention is not necessarily limited thereto, and it can be em-

ployed for holding cans, packages, and boxes containing a great variety of goods. The sections are packed separately and are then fastened together in the manner heretofore described, and therefore no repacking or rearranging of the articles in the sections are required when the boxes are opened. The sections are so constructed that when arranged in display position the articles in the sections are in plain view and will maintain their neat and regular arrangement. The front 9 of each section forms a stop to prevent the articles in the section from slipping out and also closes the section at the bottom thereof, so that it will not gather dirt if standing on the floor. While I have shown this front made of a solid strip, it is within the scope of my invention to provide a strip of any suitable kind to prevent the articles in the section from slipping out at the bottom thereof.

Without limiting myself to the exact construction and arrangement of parts herein

shown and described, what I claim, and desire to secure by Letters Patent, is—

A packing-box composed of two independent sections adapted to be fastened together for shipping and separated to display the articles therein, each of said sections comprising a bottom formed by an end of the box, a back formed by the front or back of the box, a low front, sides having their upper edges inclined and extending from the upper edges of the front to the back at a point below the top thereof, the upper end of the back of each section extending above the sides to form a handle and overlapping the front of the other section when said sections are fastened together to form the box, and flanges on the inclined edges of the sides of each section to overlap the edges of the articles therein.

ARTHUR ACHESON.
